CLAIM

The ornamental design for a latching ends of a polymer ligating clip, as shown and described.

DESCRIPTION

FIG. 1 is a perspective view of the front side, right side, and top side of a latching ends of a polymer ligating clip showing the new design.

FIG. 2 is a perspective view of the back side, left side, and bottom side thereof;

FIG. 3 is a perspective view of the front side, left side, and top side thereof;

FIG. 4 is a perspective view of the back side, right side, and top side thereof;

FIG. 5 is a front side elevational view thereof;

FIG. 6 is a top plan view thereof;

FIG. 7 is a bottom plan view thereof; and

FIG. 8 is a left side elevational view thereof;

FIG. 9 is a right side elevational view thereof;

FIG. 10 is a perspective view of the top side, front side, and right side thereof; and,

FIG. 11 is an enlarged cross section of the hook end of the latching ends of a polymer ligating clip taken along line 11-11 in FIG. 10.

The back side elevational view is a mirror image of the front side.

The dash-dot-dot-dash broken lines immediately adjacent shaded surfaces represent boundaries of the claimed design. The even broken lines shown in the figures are for the purpose of illustrating portions of latching ends of a polymer ligating clip and form no part of the claimed design.
